UNITED STATES PATENT OFFICE.

JOHN A. HULIT, OF TOPEKA, KANSAS.

SELECTIVE CALL APPARATUS.

No. 850,837.

Specification of Letters Patent.

Patented April 16, 1907.

Application filed July 13, 1905. Serial No. 269,470.

To all whom it may concern:

Be it known that I, JOHN A. HULIT, a citizen of the United States of America, residing at Topeka, in the county of Shawnee and 5 State of Kansas, have invented new and useful Improvements in Selective Call Apparatus, of which the following is a specification.

The invention relates to devices whereby any one of a number of stations on a single 10 electric circuit may be called or signaled without calling or signaling the other stations, useful on telegraph-lines, party-line telephone systems, and elsewhere. Such devices are usually operable by combinations 15 of electrical impulses and spaces, the respective stations being responsive only to certain predetermined combinations of signals.

It also relates to a system of this kind in which the instruments may be called individually or in groups or all in concert at the 20 will of the calling operator.

A patent has already been granted to me covering, broadly, some of the features shown herein—to wit, Patent No. 795,839, dated 25 August 1, 1905, for a selective call apparatus; but the improvements herein shown and claimed are not limited in their scope to use in connection with the devices shown in that application except as expressly limited in the 30 appended claims; but they may be used with other mechanisms as well.

Objects of the present invention are to improve generally upon machines of this general nature and upon the several parts thereof, to reduce the number of parts, to make the calling easier without in the case of the telegraph-call rendering the instrument responsive to ordinary characters, to simplify the mechanism, to provide an improved balance-bar of simple construction, to provide a balance-bar which moves slowly in both directions, to provide such a balance-bar moving slowly in both directions which will throw off the holding-pawl in one extreme position 40 and throw it on in the other extreme position, to simplify in particular the selective feature, and to accomplish the various objects hereinafter explained in detail.

In this invention, as in the former one, I 45 preferably provide a combination of devices, including a ratchet, whereby a certain signal will progress all the ratchets and another certain signal will normally return them to initial position, together with devices selectively arranged and coöperating with the respec-

tive ratchets for preventing the return of the ratchet at times notwithstanding the sending of the signal, which would normally have that effect.

In the former invention the trip-signal was 60 a dot and the progressing-signal was a long dash, while in the present invention the progressing-signals are a series of long dashes with short spaces between and the returning or trip signals are simply long spaces, so that 65 with the present invention the permutation may be accomplished by dividing the total number of dashes into groups with long spaces between the groups and short spaces between successive dashes in the same group, 70 as will be hereinafter explained in detail.

The invention consists of the parts, improvements, and combinations particularly pointed out and claimed herein.

In the drawings accompanying and forming part of this specification and in the description thereof I illustrate the invention in its preferred form and show the best mode of applying the principles thereof; but it is to be understood that the invention itself is not 80 confined to the drawings and the description of the drawings, that it may be applied to other uses, and that parts and combinations thereof as specifically and separately claimed may be used in connection with other devices 85 of similar general nature, and that I contemplate changes in form, proportion, material, arrangement, transposition of parts, and the substitution of equivalent members without departing from the spirit of the invention. 90

In the drawings I have shown the invention applied to a telegraph-line, the machine proper being included in a circuit controlled by the back contact of the relay-armature, whereby on a normally open main-line circuit the local machine-circuit is normally 95 closed.

Figure 1 is a side elevation of the mechanism of the selective calling-machine, the near frame-plate and the ratchet-spring being removed and some of the parts being shown in section, the view being taken approximately along the line 1' 1' of Fig. 3. Fig. 2 is supplemental to Fig. 1 and shows the parts immediately concerned in shifting the switch, 100 such parts being hidden from view in Fig. 1 by the upright frame-plate. Fig. 3 is a top or plan view of the machine, one of the stay-rods being removed wholly and another partially. Figs. 4 and 5 are drawn to show, in 105

connection with Fig. 1, the operation of the ratchet, the ratchet-progressing mechanism, and the throw-off mechanism for returning the ratchet to initial position. In Fig. 4 I show how the holding-pawl is thrown off, permitting the ratchet to be returned when the electromagnet is energized, and in Fig. 5 I show the same operation except that the selective devices are brought into play so as to prevent the return of the ratchet, notwithstanding the making of the signal which would normally throw off the holding-pawl and return the ratchet to initial position. Figs. 6 and 7 are details of parts not clearly disclosed in the preceding figures. Fig. 8 shows the operation of the switch-shifting mechanism, the switch being here represented as thrown by the ratchet upon the sending of the proper combination for this particular machine. The frame-plate is here shown in outline, as the switch itself and its immediately-associated parts, including the block of insulation on which it is mounted, are on the outside of the frame, or back of the plate shown in outline. Fig. 9 represents the ratchets of a series of six of my selective calling-machines, which may be placed on the same line and be called individually or in groups or all in concert. This view shows the novel method of permutation, the selectivity being accomplished simply by making certain of the notches deeper than the normal ones. Fig. 10 represents one manner of the local wiring in diagram.

35. Like reference numerals and letters indicate like or corresponding parts throughout the several views.

Reference is first made to the local wiring, Fig. 10. ML is the main line of a telegraph-circuit, including the relay R, of which 9 is the armature and 10 and 11 the front and back contacts, respectively. So is the sounder. LB is the local battery. Si is a suitable signaling device, as a bell, and M is the selective calling-machine, hereinafter to be described in detail, for shifting the switch S from contact 12 to contact 13. EM is the electromagnet of the machine, and 14, 15, 16, and 17 are the binding-posts. These parts are connected up with suitable wiring, and the circuits are as follows: The local sounder-circuit may be traced commencing with front contact 10, thence through wire 18", wire 18 and binding-post 14 and sounder So, wire 20, contact 12, switch S, wire 21 and binding-post 17 and battery LB, and armature 9 to contact 10. This circuit is normally open at 9 10. The selective-calling-machine circuit may be traced commencing with the back contact 11, through wire 19 and binding-post 15; electromagnet EM, wire 20, contact 12, switch S, wire 21, and binding-post 17 and battery LB, and armature 9 to back contact 11. This circuit is normally closed. The local signaling-circuit may be traced com-

mencing with the switch S, thence through wire 21 and binding-post 17 and battery LB, wire 21' and bell Si and binding-post 16, contact 13 to switch S. This circuit is normally open at S 13. The operation of the relay by 70 the main-line circuit will operate the local machine and sounder circuits in the usual manner of a pair of circuits controlled by the back and front contacts, respectively, of the main-line relay. The switch S is not directly 75 controlled by the electromagnet EM, but indirectly by the mechanism shown in the other views, and in such manner that ordinary sending will not affect it, but that each machine will be responsive only to certain 80 combinations of characters, so as to throw the switch S. When, however, the switch is shifted, the effect is that the local signaling-circuit will be closed, so as to ring the bell or do any other thing to which it is adapted, 85 and the local machine and sounder circuits will be opened at S 12, thereby diverting the current from LB to the signaling-circuit.

The signal Si may be located in any desired place, as in the operator's room, in the office, in the freight-house, his residence, or anywhere that the alarm or call is desired.

In the illustrations of the machine proper I have shown it to be provided with the four binding-posts; but obviously the fourth need not be used if a separate sounder-circuit and battery be desired, and, indeed, in respect of the wiring the arrangement may be modified to meet any condition or requirement.

Referring now to the machine itself, 101 represents the base, of metal, and 100 is the subbase, of hard wood. Most of the parts of the machine are mounted between the upright plates or standards 23 23, which are screwed to the base-plate 22 and held rigidly 105 and suitably spaced apart by the three separators or stay-rods 24 24 24. The several shafts or pivot-rods are mounted, preferably, between screw-cup bearings 87 87.

On the outside of one of the upright frame-plates 23 is secured a block of insulation, as hard rubber, by the screws 26 26. The switch S is a fine spring-wire secured to the block 25 by a plate 27, screwed thereto, which plate is connected with binding-post 17 by wire 21. The spring S extends down between the two guide-posts 28 28 and tends naturally to rest against the platinum point of the rod 13, which is connected by wire 21' to binding-post 16. The switch S is normally 110 held out of contact with 13 by the pin 12 in shaft 35, which shaft is mounted between the frame-plates 23 23, with the one end having pin 12 extending out therefrom under the block 25. The wire from binding-post 15 115 passes 19 through the electromagnet EM and thence connects 99 with the metallic base-plate 22, and thence electric connection is continued through the frame-plates 23 23 and shaft 35 to the pin 12. Binding-post 14 120

is connected with the base-plate 22 by the wire 18 and is thus connected with the pin or point 12 through the frame and shaft, but without passing through the electromagnet, in which manner the circuits are completed through the machine in the manner illustrated in the diagram Fig. 10.

The shaft 35 is provided with an upwardly-extending rod 36, a forwardly-extending rod 37, and two tail-rods 29 29, which last-named act merely as weights and stops.

On a shaft 31 is a piece 32, to which is secured a rod 30, and which is also provided with a shoulder or notch 33, engaged by the upper end of rod 36.

Normally rod 36 engages notch 33, thereby forcing the pin 12 against spring-switch S, which is forced away from the point 13, whereby the local sounder and machine circuits are normally closed at this point and whereby the local signaling-circuit is normally open, and upon raising the rod 30 (and with it piece 32 and notch 33) the rod 35 is released, thereby permitting the spring-switch S to engage point 13, the weights 29 29 turning shaft 35 far enough to make a complete disconnection between S and 12, thus opening the local sounder and machine circuits and closing the signaling-circuit. This secondary position is shown in Fig. 8.

On a shaft 41 is a spring 46, with one end attached to the shaft itself and the other end attached to the stud 47. Also secured on and to the same shaft is a ratchet-wheel 42, and also on the shaft is the elbow-shaped rod 43. The ratchet-wheel has a pin 44, which normally rests against the butting plate 45, which is secured to the two rods 45' 45'. These parts are so arranged that the spring 46 tends to keep the ratchet in normal position, with pin 44 against butting plate 45, and upon propelling the ratchet against the tension of the spring the elbow-shaped rod will lift the rod 30 until rod 36 is freed from the notch 33 so as to shift the switch, as described. In the illustration this shifting will be accomplished when the ratchet-wheel has been progressed nine notches from initial position.

On a shaft 60, pivoted between the two frame-plates, is the main propelling-lever 61, and on another shaft similarly pivoted is the bell-crank lever 61', to the upper arm of which the main lever is connected by a link 62, and to the lower end of which is affixed the armature-bar 63, controlled by the electromagnet EM, the two spools of which are secured by heel-plate 59 to lug 49. A small wood pin 64 serves to prevent contact between the armature 63 and the cores 58 58, although any other butting plate might answer just as well. An advantage in the employment of this double lever instead of single L-shaped lever is that a long travel of the propelling end of the lever may be pro-

cured with a comparatively short travel of the armature-bar within the magnetic field of the electromagnet. This arrangement of the main propelling-lever is such that it is moved to its work to propel the ratchet upon the closing of the main-line circuit, which opens the local machine-circuit. Also the propelling-lever is moved to its work by gravity and is retracted therefrom by the energized electromagnet, it being understood that the long arm of the main lever is the heavier and that it can be adjusted by adding to or deducting from its weight, so as to operate with the exact force required, and that fluctuations in the amount of current will not injuriously affect the working of the machine.

At the other end of the lever 61 is pivoted the propelling-pawl 65, a light spring 69 holding it against a stop-pin 70. The parts are so arranged that when the magnets are energized lever 61 is thrown up against the buffer-rod 80 with pawl 65 clear of the ratchet-wheel, and when the magnets are demagnetized gravity brings the lever down against another rod 81, the pawl being adjusted so as to move the ratchet forward one tooth or notch and no farther.

To a shaft 75, pivoted between the upright frame-plates, is secured a holding-pawl 73, an upwardly-extending rod 90, a downwardly-extending rod 76, a forwardly-extending rod 54, whose end may be provided with a shoe 55, and the rearwardly-extending rod 38, the parts being so weighted as to tend naturally to force the holding-pawl into engagement with the ratchet.

Obviously the closing of the main-line circuit nine times would have the effect with the mechanism so far described of shifting the switch. To make the switch-shifting mechanism responsive only to certain combinations is the object of the devices now to be described in connection with the foregoing.

To a shaft 57, pivoted between the upright frame-plates, are secured an elbow-shaped supporting-rod 58, a trip-rod 71, and a tail-rod 72 so weighted and adjusted as to tend to the position shown in Fig. 4, tail-rod 72 being down and rod 71 up, in which position rod 58 will support rod 54, (or the shoe 55 thereon,) so as to retain the holding-pawl out of contact with the ratchet-wheel; but upon depressing trip-rod 71, and thereby moving rod 58 away from under the end of rod 54, (or shoe 55,) the holding-pawl will be free to move into engagement with the ratchet-wheel.

On a pivoted shaft 66', also extending between suitable bearings on the upright frame-plates, is the main balance-bar 66, whose rearward end 67' is the heavier. This bar is adapted to move or oscillate between two extreme positions—from that shown in Fig. 1

to that shown in Fig. 4. In the first position one end strikes against the buffer 77, and in the second position the other end strikes against the buffer 80.

5 The balance-bar has at one end a tripper 78 to engage the trip-rod 38 when in the second position, and at the other end is the tripper 74, adapted to depress the trip-rod 71 in the first position. It will be observed 10 from the drawings that the balance-bar has a sufficient range of action that it may move some little distance between the extreme positions without engaging either trip-rod 38 or trip-rod 71. This is shown clearly in Fig. 15, where the balance-bar is suspended about midway between its two extreme positions and is clear of both said trip-roads.

When the balance-bar falls or has fallen to the second position (shown in Fig. 4) by its 20 own weight, so as to engage and depress the trip-rod 38, which is fastened to the shaft 75, to which the holding-pawl is also secured, the effect is to disengage the holding-pawl from the ratchet-wheel and keep it disengaged 25 therefrom all the time that the balance-bar remains in that position, and also as the other end of the balance-bar is in this position elevated, and thus frees trip-rod 71 from tripper 74, the shoe 55 and rod 54 being elevated 30 above rod 58, said rod 58, and with it the shaft 57, rod 71, and rod 72, will fall in accordance with their natural tendency, with tail-rod 72 resting on buffer 56 and rod 58 under and supporting the end of rod 54, as shown 35 in Fig. 4. Supporting-rod 58 will thus retain the holding-pawl disengaged from the ratchet until the main balance-bar is moved to its other extreme position, so as to trip the rod 71. To move the balance-bar to that other 40 position, I provide an intermediate lever or an intermediate balance-bar between the main balance-bar 66 and the main propelling-lever 61, as will now be explained.

The intermediate lever, which may also be 45 variously termed an "intermediate balance-bar" or an "auxiliary balance-bar" 40, is mounted on the pivot-rod 39, which extends, as the other pivot-rods, between suitable 50 bearings in the frame-plates 23 23. One end of this intermediate lever extends in the form of a light-wire rod 52 under a pin 53 in the side of the heavier end of the balance-bar. The other end 40' of the intermediate lever is the heavier and is heavy enough to raise the 55 heavier end of the main balance-bar when the end 40' of the intermediate bar is unsupported and permitted to fall by gravity. The intermediate lever is connected in one-way engagement with the main propelling-lever 61 60 by means of the two-legged link 50, which is pivoted in the recess 48 in the heavier end of the intermediate lever and whose legs straddle the pin 51 in the main propelling-lever, so that when the main propelling-lever is raised 65 by energizing the electromagnets the heavier

end of the intermediate lever is also raised therewith and the other end 52 is lowered, and this permits the main balance-bar to fall in accordance with its natural tendency to the position shown in Fig. 4. The main balance-bar, however, being about equally balanced and being rather heavy will move sluggishly or slowly and not quickly as the propelling-lever or the intermediate lever when the main propelling-lever is raised, and, again, 70 when the magnets are deenergized, permitting the main propelling-lever to fall quickly, the heavy end 40' of the intermediate lever will not fall quickly with the main propelling-lever, but by reason of the other end 52 engaging and raising the heavier end of the balance-bar the said end 40' will fall slowly and the heavier end 67' of the main balance-bar will be raised slowly, and thereby sent to the position shown in Fig. 1. These two 75 balance-bars together constitute a compound balance-bar which moves or oscillates slowly in both directions notwithstanding the fact that the main propelling-lever moves quickly in one direction by the force of gravity and in 80 the other by the electromagnets. These two balance-levers must be constructed with proper relation to each other, so as to move somewhat slowly, and yet their motion must be heavy or decided enough to trip the rods 85 90 95 71 and 38, respectively, as explained. Neither, on the other hand, should they be too heavy, so as to be not operable by small batteries.

As a device for manually restoring the parts 100 to initial position after the switch has been shifted, I provide the parts associated with rod 81, as follows: Said rod has a coil-spring 82 and a rod 83 engaging a buffer 80 to keep 105 said rod 81 from being turned with the tension of the spring, a forwardly-extending rod 84 to engage the under side of the propelling-lever 61, a rod 85 to engage trip-rod 38, and a tail-rod or handle 86 whereby it is operated. By depressing handle 86 (against tension of spring 82) the rod 84 raises the main 110 propelling-lever, freeing the ratchet from the push-pawl, and the rod 85 restores rod 36 to engagement with notch 33. It is seen that when the switch has been thrown rod 37 engages 115 rod 76, thereby holding the retaining-pawl out of engagement with the ratchet-wheel. The parts are so adjusted that the push-pawl is released before 37 is released from 76, thereby permitting the spring to 120 quickly restore the ratchet-wheel to initial position before the wheel is engaged by the holding-pawl. This action of restoration is practically instantaneous.

We now come to the selective features— 125 that is, the features wherein the several machines differ from each other so as to be individually responsive to signals. In the illustration the selective feature lies in making some of the teeth or notches of the ratchet— 130

wheel which are engaged by the holding-pawl deeper than the others—that is to say, all the teeth are of a normal depth except certain selected ones. Thus in the main 5 illustration the fourth and sixth notches of the ratchet-wheel are deeper than the others. In the A wheel, Fig. 9, the fourth and fifth are the deeper ones. In the C wheel the fourth and seventh, in the D wheel the fifth and 10 sixth, in the E wheel the fifth and seventh, and in the F wheel the fifth and eighth are the deeper notches. The location of these deep notches are the only parts in this arrangement in which the machines differ from each 15 other. A pin 79 projects from the side of the balance-bar 66, and said pin and the upright rod 90 are so related to each other that when the holding-pawl engages a notch of normal depth the rod will have a position out of the 20 path of said pin 79, as in Fig. 1, and when the holding-pawl engages a deep notch the rod 90 will be carried around a little farther, so as to be directly in the path of the pin 79, and thereby suspending the main balance-bar 25 66 about midway between its two extreme positions and free from both trip-rods 38 and 71, as plainly shown in Fig. 5.

In explaining the operation of my apparatus I assume that the calling instrument is 30 connected up with the circuit controlled by the back contact of the relay of a normally open circuit, as shown in the diagram Fig. 10. The electromagnet EM will therefore be normally energized, the main propelling-lever will be in raised position, the heavy end 35 40' of the intermediate lever will be raised, the main balance-bar will occupy its natural position with its heavier end 67' down against trip-rod 38, thereby throwing off the holding-pawl and raising rod 54, thereby permitting supporting-rod 58 to tilt forward under the end of said rod 54. As both the propelling-pawl and the holding-pawl are out of engagement with the ratchet, the ratchet 40 45 is held in initial position with pin 44 against butting-plate 45, with the point of the holding-pawl opposite the zero notch. These positions are shown in Fig. 4. The switch-shifting mechanism normally occupies the 50 positions shown in Figs. 1 and 2, as heretofore fully explained.

Now suppose the main line be closed. The main propelling-lever will fall, bringing the propelling-pawl into engagement with 55 the ratchet, progressing the ratchet one notch from initial position. Pin 51 is withdrawn from link 50, thereby permitting the heavier end 40' of the intermediate lever to fall by gravity, which raises the other end 52, carrying the heavier end 67' of the main balance-bar up also, and with it the rod 78 is 60 carried away from trip-rod 38. Now the balance-bar moves sluggishly or slowly, and therefore it takes some space of time for it to 65 be moved from its normal position to its other

position..with rod 74 in engagement with trip-rod 71, and in the interim the holding-pawl is held out of engagement with the ratchet by reason of rod 54 being supported on supporting-rod 58, notwithstanding the 70 withdrawing of 78 from 38. Hence if the main line be opened before the balance-bar has moved its full distance—that is, before it has brought 74 to depress 71, so as to trip 74 from under 54—the raising of the main 75 propelling-lever will take the propelling-pawl away from the ratchet, and thereby permit the ratchet to return to initial position. If, on the other hand, the main line be kept closed for some space of time, the main balance-bar will be permitted to make its full 80 stroke and depress the trip-rod 71, taking 58 away from under 54 and permitting the holding-pawl to come into engagement with the first notch of the ratchet, which position 85 is shown in Fig. 1, the ratchet being progressed one notch. Of course the parts may be so adjusted that the main balance-bar will move with the desired speed. I contemplate, however, so adjusting them that the 90 time required to make the full stroke of the balance-bar in the direction just described will be a little longer than the ordinary dash of the Morse code, so that either a dot or a 95 dash of the Morse code will have the effect of returning the ratchet to initial position, as described. The desired dash may be as long as the operator may wish to make it to be safe; but it cannot be shorter than the time required by the balance-bar to make the full 100 stroke.

If now after the long dash just described the main line be opened for some space of time, (a long space,) the parts will return to normal positions, as shown in Fig. 4, with 105 both pawls disengaged from the ratchet and the ratchet in initial position. Thus a long dash followed by a long space will still have the effect of returning the ratchet to initial position.

If, again, instead of a long space the long dash be followed by a short space, the action will be as follows: When the main propelling-bar is raised, the heavy end 40' is raised quickly with it, thereby dropping the end 52, and permitting the heavier end 67' of the balance-bar to fall, or rather to start to fall, and at the same time freeing 74 from trip-rod 71. Upon quickly closing the main line again the propelling-pawl engages the ratchet, progressing it one notch. The pin 51 is again withdrawn from 50, permitting the heavy end 40' to fall and the other end to be raised, thereby engaging the heavy end 67' of the main balance-bar and raising it again before 38 has 125 been tripped by 78, and thus a long dash followed by a short space will progress the ratchet and hold it in progressed position. Upon the second closing of the circuit of the main line at the end of the short space, which 130

brings the push-pawl into engagement with the ratchet and progresses it, the holding-pawl will by the action of the teeth against it be momentarily thrown off, and this throwing off will be sufficient to raise rod 54 and permit the rod 58 to come under it, (74 being now raised,) whereby the holding-pawl will be held disengaged from the ratchet until the main balance-bar again is brought to engage 71. Thus if the long dash and short space be followed by a dot the ratchet will be returned to initial position; but if the long dash and the short space be followed by another long dash the ratchet will be progressed two notches and will be held there until either progressed by further long dashes and short spaces or returned by a dot or a long space.

In similar manner if nine of the long dashes 20 be made in succession on the main line with the short spaces between, as just described, the ratchet-shaft will be turned to the point where arm 43 will lift 30 and release 36, thereby shifting the switch of the machine, as 25 heretofore pointed out. It is also now clear that if a long space be made between any two of the long dashes the effect will be to return the ratchet to initial position except when the holding-pawl engages a deep 30 notch, and a similar effect will follow the making of a dot. The dashes after the first one need not be so long as that one, much depending upon the relative adjustments, as well as the relative lengths of the spaces. The 35 spaces may be as short as it is possible to make them. The ratchet will be duly progressed by reason of gravity and will quickly bring the push-pawl to its work. Although it may be that an operator will sometimes unintentionally make a dash long enough to progress the ratchet, it is not likely that any one will make the necessary succession of such characters unless he desires to make the call. The ordinary characters may thus be said to 40 be absorbed by the balance-bar. If but a single machine be placed on a line, it may be made responsive simply to the long dashes and short spaces, so as to require in the main illustration simply the making of the nine 45 long dashes with short spaces between, and no selective devices would be necessary: but if two or more be placed on the same line and it be desired to call them singly or in groups or all in concert then the selective or individual devices must be provided, and the operation of these devices in connection with the mechanism heretofore explained will now be 50 shown.

If the fourth long dash be followed by a 60 long space, with the six machines on the line as illustrated by the ratchets shown in Fig. 9, the machines having ratchets A, B, and C will not return their ratchets to initial positions, for the reason that the fourth notches 65 of these ratchets are deep ones and permit

the rod 90 to be thrown into the path of the pin 79, whereby the balance-bar is suspended on the said rod 90 without engaging 38 and throwing off the holding-pawl, notwithstanding the making of the long space, as shown in 70 Fig. 5; but this same long space will have the effect of returning the ratchets of machines D, E, and F to initial positions, because the fourth notches of these ratchets are of normal depth and keep rod 90 out of the path of pin 79, thereby permitting the main balance-bar to fall its full stroke and throw off the holding-pawl; and if this long space be followed by five long dashes with the short spaces between the switches of the first 75 three machines will be shifted and the bells rung without affecting the latter three machines. By making the combination of five long dashes, a long space, and four long dashes the bells of the latter three machines 80 will be rung without disturbing the others. Similarly by making the combination of four long dashes, a long space, two long dashes, a long space, and three long dashes the B bell will be rung without ringing the others, for 85 the reason that the long space after the sixth dash will return ratchets A and C, the long space after the fourth long dash having returned the latter three. These individual combinations may be briefly designated by 90 the groups of dashes thus: The individual combination for the A machine is 4-1-4; B, 4-2-3; C, 4-3-2; E, 5-1-3; E, 5-2-2; F, 5-3-1. The group-call for the A, D, E, and C machines is 4-5, for the A, D, E, and F machines is 5-4, 95 for the B and D machines 6-3, for the C and E machines 7-2, while nine straight dashes will call them all.

The method of permutation herein followed is the same as that shown in the former patent referred to except that here I use the long space as a throw-off signal, while in the former device I use a dot, and this method, broadly speaking, is fully covered and explained in that application.

What I claim is—

1. The combination of the switch-shifting ratchet, a propelling device and a holding-pawl therefor, and a compound balance-bar adapted to move slowly by the force of gravity in both directions.

2. The combination of the switch-shifting ratchet, a propelling device and a holding-pawl therefor, and a compound balance-bar adapted to move slowly by the force of gravity in both directions.

3. The combination of the switch-shifting ratchet, a propelling device and a holding-pawl therefor, a compound balance-bar adapted to move slowly by the force of gravity in both directions, together with suitable connections whereby the balance-bar in one position throws off the holding-pawl and in another position engages it with the ratchet.

4. The combination of a switch-shifting

ratchet, a propelling device and a holding-pawl therefor, and a compound balance-bar adapted to move slowly by the force of gravity both ways between two positions and adapted in one position to throw off the holding-pawl and in the other position to throw it into engagement with the ratchet.

5. The combination in an apparatus of the kind set forth of the combination-ratchet and propelling and holding pawls therefor, a compound balance-bar adapted to move slowly by the force of gravity both ways between two positions and adapted in one position to throw off, and in the other position to throw on, the holding-pawl, and suitable means for operating the propelling-pawl and the balance-bar.

6. The combination of a switch-shifting ratchet, a propelling device and a holding-pawl therefor, a compound balance-bar adapted to two positions and to move slowly by the force of gravity both ways therebetween, means for operating the propelling devices and the balance-bar, and suitable connections intermediate the balance-bar and the holding-pawl whereby the balance-bar is adapted in one position to throw off, and in the other position to throw on, the holding-pawl.

30 7. The combination of the switch-shifting ratchet, a propelling device and a holding-pawl therefor, a compound balance-bar adapted to two positions and to move slowly by the force of gravity both ways therebetween, and suitable means intermediate the balance-bar and the ratchet whereby the balance-bar is adapted in one position to throw off the holding-pawl, and in the other position to throw it on.

40 8. The combination of the switch-shifting ratchet, a propelling device and a holding-pawl therefor, a balance-bar adapted to two positions and to move slowly therebetween, suitable means intermediate the balance-bar and the ratchet whereby the balance-bar is adapted in one position to throw off the holding-pawl, and in the other position to throw it on, and means selectively arranged to prevent the return of the ratchet notwithstanding the throw-off signal.

50 9. The combination of the switch-shifting ratchet, a propelling device and a holding-pawl therefor, a balance-bar adapted to two positions and to move slowly both ways therebetween, suitable means intermediate the balance-bar and the ratchet whereby the balance-bar is adapted in one position to throw off the holding-pawl and in the other position to throw it on, and means selectively arranged and coöperating with the ratchet for preventing the balance-bar from throwing off the holding-pawl.

60 10. The combination of the switch-shifting ratchet, a propelling device and a holding-

pawl therefor, a balance-bar adapted to two 65 positions and to move slowly both ways therebetween, suitable means whereby the ratchet is adapted in one position to throw off the holding-pawl and in the other position to throw it on, a trip device for preventing the balance-bar from throwing off the holding-pawl and means coöperating with the ratchet and selectively arranged for bringing said trip device into play.

11. The combination with the ratchet, a 75 propelling device and a holding-pawl therefor, a balance-bar adapted to two positions and to move slowly both ways therebetween, suitable means whereby the balance-bar is adapted in one position to throw off the holding-pawl and in the other to throw it on, a trip device for preventing the return of the ratchet notwithstanding the operation which normally throws off the holding-pawl, and means coöperating with the ratchet and selectively arranged for bringing said trip device into play.

12. The combination with the ratchet, a 80 propelling device and a holding-pawl therefor, a balance-bar adapted to two positions 90 and to move slowly both ways therebetween, suitable means whereby the balance-bar is adapted in one position to throw off the holding-pawl and in the other to throw it on, a trip device to prevent the balance-bar from 95 throwing off the holding-pawl and teeth of extra depth in the ratchet engaged by the holding-pawl and selectively arranged to bring said trip device into operation.

13. The combination of a retractile switch-shifting device, propelling and detaining means therefor, and a compound balance-bar adapted to two positions and to move slowly 105 by the force of gravity both ways therebetween, and suitable means whereby the balance-bar in one position throws off the detaining means and in the other position throws it on.

14. The combination of a retractile switch-shifting device, propelling and detaining 110 means, therefor, a balance-bar adapted to two positions and to move slowly both ways therebetween, suitable means whereby the balance-bar in one position throws off the detaining means and in the other position throws it on, and devices coöperating with the switch-shifting device for selectively preventing the return of said device notwithstanding the operation of the balance-bar normally tending to throw off the detaining means.

15. The combination with a ratchet and propelling and holding pawls therefor, of a throw-off for the holding-pawl and actuating means for the propelling-pawl and the throw-off, a trip to prevent the said throw-off from, 120 engaging the holding-pawl, and notches of extra depths selectively arranged for bringing said trip into operation.

16. The combination with a ratchet and propelling and holding pawls therefor, of a balance-bar for controlling the holding-pawl, and notches in the ratchet of other than normal depth and selectively arranged for preventing at times the balance-bar from throwing off the holding-pawl.
17. The combination with a ratchet having two depths of teeth and propelling and holding pawls therefor, a balance-bar controlling the holding-pawl, actuating means for the propelling-pawl and for the balance-bar, and devices controlled by the ratchet-teeth for preventing at times according to the depth of the tooth engaged the return of the ratchet notwithstanding the action of the balance-bar normally tending to throw off the holding-pawl.
18. The combination of the ratchet and propelling and holding pawls therefor, a main propelling-lever and an electromagnet for actuating the same, a main balance-bar tending normally to throw off the holding-pawl and adapted in another position to throw it on, and an auxiliary balance-bar tending naturally to force the main balance-bar to its second position but held normally in a secondary position permitting the main balance-bar to assume its normal position, a trip for preventing the main balance-bar from throwing off the holding-pawl and means coöperating with the ratchet and selectively arranged for bringing the trip into operation.
19. The combination of the ratchet and propelling and holding pawls therefor, a main propelling-lever and an electromagnet, a main balance-bar adapted to two positions and tending naturally to one position, and an intermediate balance-lever tending naturally to force the main balance-bar from its natural position and connected in one-way engagement with the main propelling-lever.
20. The combination of the ratchet and the holding and propelling pawls therefor, a main propelling-lever and an electromagnet, the main balance-bar and an auxiliary balance-bar actuating the main balance-bar in one direction whereby the main balance-bar moves slowly in both directions, and devices whereby in one position the main balance-bar throws off the holding-pawl and in the other throws it on.
21. The combination of the electromagnet and a main propelling-lever, a ratchet and push and holding pawls therefor, a gravity-operated main balance-bar, and a gravity-operated auxiliary balance-bar actuating the main balance-bar in one direction whereby the main balance-bar moves slowly by the force of gravity in both directions.
22. The combination of the ratchet and push and holding pawls therefor, an electromagnet and a main propelling-lever, a balance-bar adapted to move slowly in both directions between two positions and to throw off the holding-pawl in one position and to throw it on in the other, a supporting-rod to support the balance-bar free from the holding-pawl, and selective devices coöperating with the ratchet for operating said supporting-rod.
23. The combination of a switch-shifting ratchet and push and holding pawls therefor, an electromagnet and a main propelling-lever, a main balance-bar tilted in one way by gravity, an auxiliary balance-bar tilted in one way by gravity to move the main balance-bar against the force of gravity and connected in one-way engagement with the main propelling-lever, and the selective devices coöperating with the ratchet to prevent the balance-bar from throwing off the holding-pawl.
24. The combination of a switch-shifting ratchet and push and holding pawls therefor, an electromagnet and a main propelling-lever, a main balance-bar tilted in one way to throw off the holding-pawl by gravity, an intermediate balance-lever connected in one-way engagement with the main propelling-lever, and also connected in one-way engagement with the main balance-bar and adapted to move the main balance-bar by gravity to throw on the holding-pawl, and devices selectively arranged and coöperating with the ratchet to prevent the return of the ratchet notwithstanding the operation of other parts normally adapted to return the ratchet.
25. The combination of a switch-shifting ratchet and push and holding pawls therefor, an electromagnet and a main propelling-lever, a main balance-bar tilted in one way by gravity to throw off the holding-pawl, and an intermediate balance-lever connected in one-way engagement with the main propelling-lever and also connected in one-way engagement with the main balance-bar and adapted by gravity to move the main balance-bar to throw on the holding-pawl.
26. In mechanism of the kind described, the combination of the shaft 35 and a tripper therefor controlled by the ratchet and having the pin 12, the ratchet and mechanism for operating the same, the spring-switch S, and the contact 13.
27. In mechanism of the kind set forth, the combination of the switch-shifting ratchet, propelling mechanism therefor, a balance-bar, a holding-pawl tending naturally to engage the ratchet and adapted to be thrown off by the balance-bar, a trip-support 58 tending naturally to free the holding-pawl from the ratchet and adapted to be thrown from its natural position by the balance-bar.
28. The combination of the switch-shifting ratchet and propelling and holding pawls therefor; a circuit including a battery and an electromagnet; a propelling-lever con-

trolled by the electromagnet; together with suitable mechanism whereby a stroke of the lever will propel the ratchet a short stroke not holding it progressed and a long stroke throwing on the holding-pawl and whereby a short space between strokes will not throw off the holding-pawl and a long space will return the ratchet.

29. The combination of the switch-shifting ratchet and propelling and holding pawls therefor; a circuit including a battery and an electromagnet; a propelling-lever controlled by the electromagnet; together with suitable mechanism whereby a stroke of the lever will 15 propel the ratchet a short stroke not holding it at its progressed stage and a long stroke throwing on the holding-pawl and whereby a short space between strokes will not throw off the holding-pawl and a long space will return the ratchet; together with devices selectively arranged to prevent the return of the ratchet notwithstanding the long space.

30. The combination of a series of selective calling devices of the kind set forth, each comprising a switch-shifting ratchet, a circuit including a battery and an electromagnet; a propelling-lever controlled by the electromagnet; suitable mechanism whereby a stroke of the lever will propel the ratchet a short stroke not holding it at its progressed stage and a long stroke throwing on the holding-pawl and whereby a short space between strokes will not throw off the holding-pawl and a long space will return the ratchet; together with devices selectively arranged to prevent the return the ratchet notwithstanding the long space; whereby all the ratchets are progressed at each stroke and all the ratchet-returning mechanisms are operated in unison, and whereby said last-mentioned mechanisms are selectively prevented from returning the ratchet notwithstanding the long space.

31. The combination of a ratchet; a balance-bar, a main propelling-lever and a propelling-pawl; a holding-pawl; a trip-support for the balance-bar adapted in one position to sustain the bar away from the holding-pawl, and in another position to permit the bar to throw off the holding-pawl; and devices selectively arranged to control said trip-support.

32. A series of ratchets; a holding-pawl, a propelling-pawl, and a balance-bar coöperating with each ratchet; and a trip device controlled selectively by the ratchet and adapted in one position to permit the balance-bar to throw off the holding-pawl and in another position to keep the bar free from the holding-pawl.

33. The combination of the main lever; a ratchet and holding and propelling pawls therefor; a balance-bar; and a trip device se-

lectively controlled by the ratchet for controlling the action of the balance-bar with relation to the holding-pawl.

34. The combination of a switch-shifting ratchet, a propelling device and a holding-pawl therefor, a balance-bar adapted to move between two extreme positions and to be moved in at least one direction by the force of gravity, together with suitable means whereby the bar in one position throws off the holding-pawl and in the other extreme position throws it back into engagement with the ratchet, the holding-pawl being so arranged as not to be returned to the ratchet until positively acted upon by the balance-bar at the end of its stroke.

35. The combination of a switch-shifting ratchet, a propelling device and a holding-pawl therefor, a balance-bar adapted to move slowly both ways between two extreme positions and being adapted in one of said extreme positions to throw off the holding-pawl and in the other of said extreme positions to throw it into engagement with the ratchet, and said holding-pawl being so arranged as not to engage the ratchet until so acted upon by the balance-bar.

36. The combination of a switch-shifting ratchet, a propelling device and a holding-pawl therefor, a balance-bar adapted to move slowly both ways between two extreme positions and being adapted in one of said extreme positions to throw off the holding-pawl and in the other to throw it into engagement with the ratchet, said holding-pawl being so arranged as not to engage the ratchet until so acted upon by the balance-bar; together with means selectively arranged for preventing the balance-bar from throwing off the ratchet.

37. The combination of a switch-shifting ratchet, a propelling-lever and a detent therefor, a slowly-moving throw-off controlled by the propelling-lever, said propelling-lever being arranged to propel the ratchet at all times independently of the throw-off.

38. The combination of a switch-shifting ratchet, a propelling-lever and a detent therefor, a balance-bar acting by its own force to throw off the detent, said propelling-lever being adapted to propel the ratchet at all times independently of the balance-bar, to restore the balance-bar upon its back stroke and to release the balance-bar on its forward stroke.

39. The combination of a switch-shifting ratchet, a propelling-lever and a detent therefor, a balance-bar acting by the force of gravity to throw off the detent; said propelling-lever being adapted to propel the ratchet at all times independently of the balance-bar, to restore the balance-bar on its return stroke and to release the balance-bar on

its forward stroke so that said balance-bar may then start upon its travel toward the detent.

40. The combination of a switch-shifting ratchet, a propelling device and a holding-pawl therefor, a throw-off, means coöperating with the ratchet and selectively arranged and acting directly upon the holding-pawl

for preventing the throw-off from acting upon the said holding-pawl.

In testimony whereof I have hereunto set my hand in the presence of witnesses

JOHN A. HULIT.
